CLAIM

The ornamental design for a cannula assembly, as shown and described.

DESCRIPTION

FIG. 1 is a top, front, and right side perspective view of a cannula assembly embodying our new design.

FIG. 2 is a rear, top, and left side perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The references to "left," "right," "front," "rear," "top," and "bottom" in the figure descriptions are not meant to require certain in-use orientation; the cannula assembly according to the claim design may be used in any orientation.

Broken lines are used to illustrate features of the cannula assembly which form no part of the claimed design.
